UNITED STATES PATENT OFFICE.

GLADYS MATSON STEWART, OF CINCINNATI, OHIO.

DESIGN FOR A GIRL'S DRESS.

Application filed April 5, 1922. Serial No. 1,545. Term of patent 3½ years.

To all whom it may concern:

Be it known that I, GLADYS MATSON STEWART, a citizen of the United States of America, residing at Cincinnati, in the county of Hamilton and State of Ohio, have invented a new, original, and ornamental Design for a Girl's Dress, of which the following is a specification, reference being had to the accompanying drawing, forming part thereof.

The view shown is a front perspective view of a girl's dress, embodying my design.

I claim:

The ornamental design for a girl's dress, as shown.

GLADYS MATSON STEWART.
